REFRIGERATOR DEFROSTING TIMER

David Morrison, Manitowoc, Wis., assignor to
Paragon Electric Company, Two Rivers, Wis., a
corporation of Wisconsin

Application March 29, 1950, Serial No. 152,733

7 Claims. (Cl. 200—33)

1

The present invention relates particularly to timers adapted to open and close the electrical circuits for refrigerators in order to effect automatic defrosting at regular intervals; although the use of the invention is not limited to this field.

In my prior application, Ser. No. 50,902, filed September 24, 1948, I have disclosed a defrosting system of the type just described. The present invention may be said to have for its object to produce a timer which is simpler in construction than that disclosed in the aforesaid application, and which is reliable, efficient in operation and very durable.

The various features of novelty whereby the present invention is characterized will hereinafter be pointed out with particularity in the claims, but, for a full understanding of the invention and of its objects and advantages, reference may be had to the following detailed description taken in connection with the accompanying drawings, wherein:

Figure 1 is a perspective view of a timer embodying the present invention, the conventional casing being omitted; Fig. 2 is a top plan view of a part of the timer, with the combined knob and pointer omitted; Fig. 3 is a side elevational view of the timer as it appears in and looking at it from below Fig. 2; Figs. 4 and 5 are views similar to Figs. 2 and 3, respectively, illustrating the conditions which exist at a different point in a cycle from that corresponding to Figs. 2 and 3; Figs. 6 and 7 are also views similar to Figs. 2 and 3, respectively, illustrating another set of conditions at still another point in such cycle; Fig. 8 is a section on line 8—8 of Fig. 2; Fig. 9 is a perspective view of the finger piece for adjusting one of two cams angularly with respect to the other; Figs. 10 and 11 are two perspective views of the cam to which the finger piece is connected; and Fig. 12 is a perspective view of the second of the two cams and the shaft with which it is interlocked so as to be compelled to rotate therewith.

Referring to Fig. 1 of the drawings, 15 represents a flat plate on which the various parts of the timer mechanism are mounted. On the under side of this plate is any suitable electric motor and speed reducing unit 16. Above the plate is a large gear wheel 17 in mesh with a pinion 18 that forms the last element in the gear train through which the timer mechanism proper is driven. A little above, and coaxial with, wheel 17 is a somewhat smaller gear wheel 19, and above and near the latter wheel is a third gear wheel 20, of the same diameter as and coaxial therewith. The number of teeth is not the same in gear wheels 19 and 20, as there must be at least one more tooth in one wheel than in the other. In the arrangement shown there are one hundred and twenty teeth in wheel 19, whereas there are

2

only one hundred and nineteen teeth in wheel 20. Gear wheel 17 has on the upper side a pin or post 21 on which is a loose pinion 22 that meshes with the teeth on each of the wheels 19 and 20. Above and coaxial with the gears are two superimposed cams 23 and 24, preferably of insulating material, coaxial with the three gear wheels. Above the cams is a combined pointer and knob 25. Cam 23 has a wide annular flange 23a that rests on the gear wheel or disc 20.

Plate 15 has at one end two spaced, upturned parts 15a and 15b. A slab 26 of insulating material spans the space between said upturned parts and is fixed to the latter. Carried by member 26 is a switch adapted to be controlled by the cams. The switch is shown as comprising two spring arms 27 and 28, each anchored at one end to the supporting member 26 and having portions thereof extending radially of the gear wheels over flange 23a. Switch arm 27 is bent downwardly near its free end and then horizontally to provide a toe piece 29 that normally lies near the flange on cam 23. Arm 28, the radial portion of which lies directly over the corresponding part of arm 27, is a straight piece. The switch arms are provided with cooperating contacts 30 and 31, respectively, inwardly from their free ends. When the switch is not under constraint, the contacts on the arms are pressed firmly into engagement with each other, through the spring action of the arms. In other words, the switch is self closing.

The details of essential parts that have now been described in general terms, only, are illustrated in Figs. 8-12.

As shown in Fig. 8, the large gear wheels are supported by a sturdy vertical column or post 32 fixed to and rising from plate 15. The post is reduced in diameter a short distance above the plate to provide a shoulder 33 on which gear wheel 17 rests. At a little distance above shoulder 33 there occurs a second reduction in diameter of the post to provide a shoulder 34 on which gear wheel 19 rests. A third reduction in the diameter of the post, at a still higher level, provides a third annular shoulder 35 on which gear wheel 20 rests. There is a spacer 36 around the post, between gear wheels 17 and 19.

Gear wheels 17 and 20 are loose on and rotatable about the post, whereas gear wheel 19 is fixed to the post by pressing it on, or in any other suitable way.

The body portion of cam 23 is an inverted cup the chamber 23b in which is substantially larger in diameter than the upper end of the post. Gear wheel 20 has on the upper side a tubular hub 37 that fits around the post and provides a long bearing for this wheel. Surrounding this hub, and fitting it closely, is a torsion spring 38 one end 39, of which, is engaged in a groove 23d

opening out from one side of the chamber in cam 23. This arrangement constitutes a clutch that permits the cam and gear wheel 20 to turn freely, relatively to each other, in one direction, and prevent relative movement in the opposite direction. The reason for having the clutch is to permit the cam to be turned by hand, relatively to gear wheel 20, for the purpose of selecting the point in time at which the switch shall open. In order that cam 23 may be turned by means of knob 25, I make the post tubular in form to serve as a bearing and support for loose shaft 49. This shaft contains two circumferential grooves 41 and 42 that lie, respectively, immediately below and above the post. When flat C-shaped keys 43 are entered in these grooves, the shaft is held against lengthwise displacement, while free to rotate. That part 44 of the shaft above groove 42 is flattened so that, when it is slipped through a correspondingly shaped hole in the top wall of the chamber in cam 23 and through a hub 45 projecting up from the cam, the shaft and cam are securely interlocked against turning movements relatively to each other.

Shaft 49 extends up well above cam 23, and cam 24. Cam 24 and the shaft are not interlocked against relative angular movements. It will be seen from Figs. 10 and 11 that cam 24 has on its upper side a hub 46 in the form of a sleeve slotted from top to bottom at two diametrically opposed points. A finger piece 47, best shown in Fig. 9, is slipped on this hub. This finger piece is shown as being in the form of a metal disc 48 having a stem 49 that projects radially therefrom; the outer end of the stem being bent up at right angles to the rest of the stem. The disc contains a central hole 40 to receive the hub on the cam, together with two opposed lugs 51, 51 that extend inwardly from the sides of the hole. These lugs enter the slots in the sleeve hub and interlock the cam and finger so that they must turn with each other. The shaft is provided with a groove 52, similar to grooves 41 and 42, placed a little above the lower end of the hub 46. To apply the finger piece in the assembly, the hole in the finger piece is first registered with the upper end of the shaft, with the lugs 51 at the flat sides of the latter. Then, after cam 24 has been turned with the slots in the hub registering with the lugs on the finger piece, the latter may be moved down over the hub until it reaches the level of the groove 52 in the shaft. Thereupon the finger piece may be turned until the lugs enter this groove and allow the finger piece to turn freely on the shaft. By placing the groove a little above the top of the body portion of the cam member, room is provided between the finger piece and such body portion for a spring washer 53. In making the assembly, the washer is placed in position before the finger piece is applied, so that the washer must be stressed somewhat to allow the finger piece to come down far enough to enter groove 52. Thus the cams are yieldingly pressed together, so that the upper cam is frictionally held against turning on the lower cam.

As shown in Fig. 1, the combined knob and pointer 25 has in the edge of its disc-like portion 54 a wide notch 55. The upwardly bent end of the stem member of the finger piece 47 lies in this notch, so that the angular movement of the finger piece and the upper cam, relative to the lower cam, is limited to the angular width of the notch.

The details of the two cams are best shown in

Figs. 10, 11 and 12. Thus, as shown in Fig. 12, the lower cam has an arcuate ledge, the top of which is a cam track 23^c, rising from the level of the top surface of the flange to a high level of any desired angular length. Similarly, cam member 24 has an arcuate ledge of the same radius as the other ledge and provided with a cam track 24^a that is much like the other track. Each of the two ledges terminates abruptly at the high end, and the cams are so disposed, that the high ends of both trail while the timer is operating. The parts are so proportioned that normally the free end of the lower switch arm lies below the level of the high portion of the lower cam track, and the free end of the upper arm of the switch lies below the level of the high part of the upper cam track. However, the free end of the lower switch arm lies above the level of the low advance end of the lower cam track. A further characteristic of the switch and cams is that the switch remains closed while both switch arms are above the high portions of the corresponding cam tracks. The camming ledge on the lower cam member is of greater angular length than the ledge of the lower cam. This allows the low end of the lower track to be in advance of the corresponding end of the upper track at times when the trailing ends are in the same vertical plane.

Assuming that the timer has been set and that the motor is running, pinion 22 is continuously carried around the stationary gear wheel, and is thus compelled simultaneously to resolve about its own axis. The pinion also rolls along the toothed edge of the upper gear wheel; but, because of the difference in the number of teeth in the wheels, the loose, upper gear wheel 20 completes a revolution after the pinion has engaged only one hundred and nineteen of the teeth in the stationary wheel. Therefore, wheel 20 is positively turned through an angle, corresponding to a single tooth, during each revolution of the pinion around the stationary gear wheel.

Where the timer is intended to control the defrosting of a refrigerator the mechanism may be calibrated to cause gear wheel 20 to revolve once in twenty four hours.

To determine the point in each twenty four hour cycle at which the switch opens, the combined knob and pointer 25 is turned to point to the desired hour and minute on the usual dial, not shown. To determine the length of time during which the switch remains open, finger piece 47 is shifted to adjust the positions of the cams relative to each other. When the finger piece is at one end of the notch in member 25 the switch will not open at any time; because the trailing end of the upper cam track is then directly above or, if desired, ahead of the trailing end of the lower track. When the finger piece leaves that end of the notch the cams are set to effect a switch opening once in each revolution of wheel 20, the length of time during which the switch remains open increasing as the finger piece is shifted along the notch.

The manner in which the cams operate or control the switch is apparent from the drawings. Thus, in Figs. 1, 3 and 5 both switch arms are clear of the cam tracks and the switch is closed. In Fig. 5 the lower cam has flexed both switch arms upwardly, raising the upper arm to such a level that the upper cam need not exert any lifting effort; serving merely as a support for the upper switch arm after the lower arm drops off the lower cam track at the trailing end of the latter. Thus, with the parts in the positions

shown in Fig. 5, the switch would remain closed even though the upper cam track were not present. Only when the lower arm reaches the dropping off point while the upper track still underlies the upper arm, as in Fig. 7, does the upper cam determine whether the switch shall open and how long it shall remain open.

While I have illustrated and described with particularity only a single preferred form of my invention, I do not desire to be limited to the exact details thus illustrated and described, but intend to cover all forms and arrangements that come within the definitions of my invention constituting the appended claims.

I claim:

1. In a timer mechanism, a support, two large gear wheels of the same diameter and one having a slightly larger number of teeth than the other, means for mounting said wheels on the support in coaxial relation and near each other to hold the lower wheel stationary while the other is free to revolve, a pinion meshing with both gear wheels, power means to carry said pinion bodily and continuously around said wheels, a switch mounted on the support and having two arms arranged one above the other and extending radially of the wheels at some distance above the upper wheel, two cam devices composed of insulating material positioned one on top of the other on and coaxial with the upper wheel and having thereon upwardly facing switch engaging cam tracks to engage with the corresponding switch arms once during each revolution of the upper wheel, the lower cam device having at the bottom an annular flange which at all times underlies the switch arms and prevents them from engaging the latter wheel, a one-way clutch between the upper wheel and the lower cam device, means frictionally holding the cam devices against relative rotary movements, and a finger piece on the upper cam device to shift it angularly of the lower one.

2. A timer mechanism including a support, a stationary tubular post rising from the support, a shaft rotatably mounted in and projecting up from the post, two gear wheels surrounding the post in coaxial relation to each other, the lower wheel being fixed to the post and the upper wheel being rotatable, one of the wheels containing slightly more teeth than the other, the upper wheel having a hub on the upper side, a pinion meshing with both wheels, power means to carry said pinion bodily and continuously around said wheels, a switch on said support beside the wheels, a switch actuating cam on, and rotatable with, the shaft just above the upper wheel and having thereon upwardly facing switch engaging cam tracks, said cam having in the underside a central cavity larger than said hub, a torsion spring in said cavity around the hub and anchored at one end to the cam to form a one-way clutch between the cam and the upper wheel, and a member on the upper end of the shaft for turning the shaft manually, in the direction permitted by the clutch, to shift the cam angularly relatively to the upper wheel.

3. A timer mechanism including a support, a stationary tubular post rising from the support, a shaft rotatable in and projecting up from the post, detachable key elements on the shaft above and below the post to hold the shaft in place, two gear wheels surrounding the post in coaxial relation to each other, the lower wheel being fixed to the post and the upper wheel being rotatable,

one of the wheels containing slightly more teeth than the other, the upper wheel having a hub on the top side, a pinion meshing with both wheels, power means to carry said pinion bodily and continuously around said wheels, a switch on said support beside the wheels, a switch-actuating cam on, and rotatable with, the shaft and having a cavity enclosing said hub, said cam having thereon upwardly facing cam tracks, and means in the said cavity cooperating with the cam and the hub to form a one-way clutch between the cam and the upper wheel, and a member on the upper end of the shaft for turning the shaft manually, in the direction permitted by the clutch, to shift the cam angularly.

4. In a timer mechanism, a support, a stationary tubular post rising from the support, a shaft rotatably mounted in and projecting upwardly from the post, three gear wheels surrounding and mounted on the post one above another, the upper and the lower gear wheels being rotatable on and the intermediate wheel being fixed to the post, one of the two upper gear wheels containing a slightly greater number of teeth than the other, the lowest gear wheel being of larger diameter than the others, a pinion rotatably mounted on the lowest gear wheel and meshing with both of the other wheels, power means to drive the lowest gear wheel, a switch operating cam means, composed of two members, on and rotatable with the shaft just above the upper gear wheel and each having thereon an upwardly facing switch engaging cam track, a one-way clutch between the cam and the upper wheel, one of the cam members having a limited angular movement on the other and provided with a finger piece to turn the same, a spring pressing said members together to create frictional resistance to relative angular movements, a switch on said support beside the wheels having two arms each of which extends into the path of one of said cam members, and a member on the upper end of the shaft for turning the shaft manually.

5. In a timing mechanism, a self closing switch formed of two spring arms arranged one above the other and anchored at corresponding ends while the other ends are free, the arms tending constantly to contact each other, each arm having thereon a contact piece, at some distance from the free end, to engage with the contact on the other arm, the center lines of the portions of the arms from the contact pieces to the free ends being in the same vertical plane, an upright shaft, rotatable in one direction only, beside the switch, two cams, one above the other, on and rotatable with the shaft; the lower cam having thereon an upwardly facing track that passes underneath the free end of the lower arm of the switch at a predetermined point in each revolution of the shaft, the track being so shaped that both arms are first stressed and raised while remaining in contact with each other, and are then released from this cam at a second predetermined point in each revolution of the shaft; the upper cam having thereon an upwardly facing cam track that passes under the upper switch arm, after the switch arms have been raised, this track being so shaped that it holds that arm up independently of the lower cam track during a portion of each revolution of the shaft and then releases it; and means to adjust the cams relatively to each other angularly of the shaft so as to determine the relative times at which the two cams release the corresponding switch arms.

6. In a timer mechanism, a rotatable shaft, a power-driven wheel supported independently of the shaft around and in coaxial relation thereto, said wheel having a central hub on the upper side thereof, a cam member in the form of an inverted cup on the wheel and interlocked with the shaft for rotation therewith, with said hub housed in the cavity in the cam member, the diameter of the cavity being greater than that of the hub, a torsion spring surrounding and gripping the hub, one end of the spring being free in space and the other end being anchored to the cam member thereby forming a one-way clutch between the wheel and the cam member, an upwardly facing cam track on the exterior of the cup, a second cam member surrounding the shaft above the cup and interlocked with the shaft for limited movements relatively thereto, said second cam member also having an upwardly facing cam track, an element on the upper end of the shaft to turn the same manually in the direction permitted by the clutch, a finger piece on the second cam member for shifting it, and a switch provided with two elements one of which extends into operative relation to said cam track while the other extends into the path of the track on the second cam member.

7. In a timer mechanism, a rotatable shaft, a power-driven wheel supported independently of the shaft around and in coaxial relation thereto, said wheel having a central hub on the upper side thereof, a cam member in the form of an inverted cup on the wheel and interlocked with the shaft for rotation therewith, with said hub

5 housed in the cavity in the cam member, the diameter of the cavity being greater than that of the hub, a torsion spring surrounding and gripping the hub, one end of the spring being free in space and the other end being anchored to the cam member and thereby forming a one-way clutch between the wheel and the cam member, an arcuate cam track on the exterior of the cup, a second cam member, provided with an arcuate cam track, surrounding the shaft above the cup and interlocked with the shaft for limited movements relatively thereto, an element on the upper end of the shaft to turn the same manually in the direction permitted by the clutch, a finger piece on the second cam member for shifting it, and a self-closing switch composed of two spring arms arranged one above the other, anchor means fixedly supporting corresponding ends of the arms while the other ends stand free, said arms extending radially into the paths of the corresponding cam tracks.
